UNITED STATES PATENT OFFICE.

ALLEN A. HORTON, OF DETROIT, MICHIGAN, ASSIGNOR TO BURROUGHS ADDING MACHINE COMPANY, OF DETROIT, MICHIGAN, A CORPORATION OF MICHIGAN.

ADDING MACHINE.

1,415,174.

Specification of Letters Patent.

Patented May 9, 1922.

Application filed August 30, 1915. Serial No. 48,008.

To all whom it may concern:

Be it known that I, ALLEN A. Horton, a citizen of the United States, residing at Detroit, in the county of Wayne and State of Michigan, have invented certain new and useful Improvements in Adding Machines, of which the following is a specification.

This invention relates to the general type of adding machine illustrated in my prior 10 Patent No. 1,016,501 issued February 6, 1912. In this type of adding or calculating machine the numeral wheels are driven by depression of keys as distinguished from that other well-known type sometimes termed 15 "key-set and crank-operated." The main object of the present invention is to provide means for resetting an individual numeral wheel to zero. It is of course common in machines of the type in question to reset all 20 of the numeral wheels to zero when a series of registrations have been completed and it is desired to begin a new series. The present invention has to do more particularly with the correction of error in key depression. It is common to provide for this in the 25 other type of machine above mentioned where the correction involves merely release of an erroneously depressed key. In the type of machine here concerned, however, the depression of a key turns the associated numeral 30 wheel. Consequently correction of an error in key depression requires the resetting of that wheel to zero or else a more or less involved subtraction operation by recourse to 35 complementary adding. Of course resetting of all wheels to zero, as commonly practiced in prior machines of this type, might be practiced for purposes of correcting error in key depression, but this would in many instances involve unnecessary canceling of 40 registrations upon wheels other than that associated with the erroneously depressed key, and, in the case of the error occurring after a considerable number of operations has 45 been performed in doing a certain calculation all the work would have to be done over again. By my present invention I provide for singling out any one of the wheels and individually resetting it to zero without necessarily disturbing any of the other wheels, 50 and thereby correcting an error in key depression without the necessity of doing involved subtraction or of canceling the registrations upon all of the wheels. (In case of 55 errors in key-depression that cause one or

more erroneous carries to take place, then the correction would of course be less simple though the individual zeroizing keys could still be employed to advantage.) At the same time I make adequate provision for 60 executing a complete canceling or zeroizing operation and I do this by collectively operating the same devices which are individually operated for resetting wheels singly.

Another object of the present invention is 65 to provide for subdividing the machine so that independent accumulations of registered amounts or sums may be carried along in the same machine. In machines of the other type above mentioned this is a familiar practice and is commonly referred to as a "split," but in those machines the splitting or subdividing is usually confined to the printing or recording department of the machine. In 70 machines of the type here concerned there is 75 no printing or recording department, so the splitting or subdividing is done in the accumulating mechanism. In carrying out this part of my invention, according to the embodiment thereof here shown, I accomplish 80 the splitting or sub-division by use of the same manipulative means which serve for individually resetting the wheels to zero. Thus certain special keys which through appropriate connections serve to disable cer- 85 tain back-stop or restraining devices are also endowed with the capacity for setting cer- 90 tain stops to hold stationary the numeral wheels. By selecting one of these special keys and operating it in a prescribed manner 95 the stop may be applied to the numeral wheel next beyond or to the left of a right hand section or subdivision of the accumulator and carry-transmission thereby inter- 95 rupted so as to separate that right-hand sec- 100 tion or subdivision of the accumulator from the section or subdivision beyond or to the left of the said wheel.

In the drawings which accompany and 100 form part of this specification Fig. 1 represents in left side elevation with some parts in cross-section, the forward portion of a machine having my invention embodied therein, all parts appearing in normal condition; Fig. 2 is a broken sectionalized plan 105 view of the same portion of the machine; Fig. 3 is a sectionalized front elevation thereof; Fig. 4 is a skeletonized perspective 110 of one group of elements together with certain parts common to the several groups;

Fig. 5 is a view generally similar to Fig. 1 but illustrating the effect of depressing one of the special keys for individually zeroizing a numeral wheel; Fig. 6 is a like view 5 but illustrates the effect of further manipulation of the key for purposes of splitting or subdividing the machine; Fig. 7 is still another view of the same general character but illustrating the effect of pulling forward 10 the zeroizing handle for collectively resetting the wheels to zero; Fig. 8 is a fragmentary sectional plan view taken substantially 15 on the line 8—8 of Fig. 1; Fig. 9 is a detail sectional elevation of ratchet and pawl driving devices.

While the machine to which my invention relates is of the general type of that disclosed in my above-mentioned patent, the 20 herein disclosed specific embodiment of the invention is one adapted to the peculiar accumulating mechanism of the Gooch Patent No. 1,128,679 issued February 16, 1915, combined with the overthrow preventing devices of the later Gooch Patent No. 1,150,937 25 issued Aug. 24, 1915. Furthermore the key-driven-actuator mechanism corresponds with that which is the subject of my prior Patent No. 1,156,600, issued October 12, 1915.

In another prior Patent No. 1,326,504 issued December 30, 1919 I have shown zeroizing mechanism of the same character as that herein shown as regards the collective resetting of wheels to zero. This mechanism provides for the resetting of wheels, not as 30 in the machine of my aforesaid patent by forward turning and successive carry-transmission, but by utilizing the carrying springs to turn the wheels backward to zero. The 35 present invention, according to the present specific embodiment thereof, involves certain modification of that zeroizing mechanism of my just-mentioned patent, whereby a like zeroizing process may be practiced upon a single selected numeral wheel.

The numeral wheels themselves are designated by the reference letter A and, as in the case of the machine of the said Gooch Patent 1,128,679, sun gears P and cams G are secured to the left-hand sides of said 50 wheels, and oscillating gear carriers L support pinions O in mesh with said sun gears and pinions N in mesh with internal gear teeth of discs C. The latter are secured to the hubs of other sun gears E with which 55 mesh broad planet gears D which also mesh with internal gears F' on the numeral wheels. The reference letter A' designates the gears which carry said planet gears D and which are driven from the keys through 60 the medium of transmission gears E² in mesh with said gears A' and having ratchet elements of certain one-way driving connections, other elements of which are oscillated by the actuators which the keys operate 65 upon.

The above-mentioned oscillating gear carriers L intermesh with segments H as in the construction shown in Figs. 10 to 12 of said Gooch Patent 1,128,679 which segments are portions of levers having studs H² engaging 70 the peripheries of the cams G. Springs J are applied to forward branches of these levers and store power for effecting carry-transmission from wheel to wheel as described in detail in said Gooch patent. 75

Carry-transmission from one wheel to another involves a one-fifth rotation of an intermediate gear disc C in a counter-clockwise direction as viewed from the right. The process of zeroizing by backward rotation of 80 a numeral wheel, as here concerned, involves the interposition of a lock to prevent such turning of an intermediate gear disc and involves application of the power stored in the carrying spring J to rotate the numeral 85 wheel to the right of that gear disc backward, by reason of the rolling of the pinion N upon the internal gear as a fixed rack and the consequent rotation of the companion pinion O in a clockwise direction and the sun gear P in a counterclockwise direction. In order that this action may take place 90 it is necessary to disable back-stop and restraining devices which otherwise would prevent backward turning of the numeral wheel, 95 and these I shall later on refer to in detail.

Referring now to the means employed for locking the intermediate gear disc C, each of said discs carries, projecting from its left-hand side, five equispaced studs or pins e. 100 Levers 2 are pivoted upon a frame cross rod 3 and formed with hooks 2^a to engage over said studs, there being one lever 2 for each gear disc. The end edge of each hook 2^a is beveled to constitute a cam so that when the upper arm of the lever swings forward the gear disc C will be forced in a clockwise direction to a slight extent swinging the gear carrier L clockwise and the lever H counterclockwise so as to separate the stud H² from 105 the periphery of the cam and eliminate friction which would interfere with the reverse turning of the numeral wheel. The lower arms of said levers 2 have cam slots by which to vibrate the levers, and upon the cross rod 3 there are mounted other levers 4 with similar cam slots in their lower arms and with hooks at the ends of their upper arms to coact with lugs A³ on the numeral 110 wheels for preventing overthrow of the latter beyond zero position under backward rotation. 115

The above described locking and overthrow preventing devices are the same as shown and described in my said Patent No. 1,326,504, and the formation of the cam slots is such as to provide for movement of the overthrow preventing levers 4 in advance of the levers 2 in order to avoid any possible 125 interposition of the wheel lugs A³ in the 130

paths of the hooks 4^a. In the construction of said patent there is only collective rocking of the levers 2 and 4, whereas, for the purposes of the present invention, one 5 pair of levers 2, 4, may be operated independently of all of the other levers. This involves modification in the character of the rocking or oscillating structure whereby the levers are vibrated, and I shall next point 10 out the details of this new construction.

A rock shaft S is employed as in the prior constructions but the levers 2 and 4 are not vibrated simply by the cross rod of a bail secured to that rock shaft, as in my last- 15 mentioned patent. There are rigidly secured to that rock shaft a series of arms or fingers 5 which serve the purposes of the bail in my prior construction but which are so related to the said levers that the latter may 20 be vibrated independently. Thus there is journalled upon the hub of each arm 5, between that arm and a shoulder of the hub (Fig. 8) another arm 6 which carries a stud 25 or pin 6^a projecting to the right under the end portion of the arm 5. A spring 7 coiled around the shaft S is anchored at one end in the arm 5 and at its other end engages under the said pin 6^a so as to normally hold the latter against the under edge of said 30 arm 5 as shown in Fig. 7. Obviously this arrangement provides for swinging of the arm 6 independently of the arm 5 in opposition to said spring, and that is what occurs when the associated numeral wheel is individually 35 reset to zero, whereas when the wheels are collectively zeroized the arms 5 operate upon the pins 6^a. From the opposite or left-hand side of each arm 6 there projects another pin 6^b which occupies the cam slots 40 of the associated pair of levers 2, 4, performing the function of the cross rod of the bail in the construction of my last-mentioned application and the further function of that cross rod in insuring a zero-setting movement of the associated lever H. Thus said 45 pin 6^b is adapted to operate upon the rearwardly extending lower arm H^a of the said lever, as illustrated in Fig. 7. The rocking of the shaft S for collective zeroizing of the 50 wheels is done through the same sort of connections as illustrated in my before mentioned Patent 1,016,501 and in said Gooch Patent 1,128,679, these connections being indicated by dotted lines in Fig. 7.

55 Referring next to the manipulative means for individually zeroizing the wheels, I employ a set of keys which protrude at the front of the machine, the key for the units wheel being designated by the numeral 8 and 60 those for other wheels by the numeral 8^a. These keys operate levers which depress the respective stud-bearing arms 6. The lever for the units order key is designated 8^b and that for the higher order keys 8^c. The occasion 65 for distinguishing between the units

order key and the others is that the latter function also for effecting the split or subdivision whereas of course the units key is not called upon in any such capacity. These levers 8^b and 8^c are journalled at their rear 70 ends upon a frame cross rod 9 and they extend forward over the rock shaft S being given a goose-neck formation to provide for the necessary degree of depression, said levers at points forward of said shaft being 75 formed with lateral lugs 8^d standing over the respective studs or pins 6^a, as most clearly seen in Fig. 3.

Obviously the depression of one of the aforesaid levers 8^b, 8^c will depress the associated arm 6 and thereby rock the levers 2 and 4 and bring about the conditions above described for utilizing the power stored in the spring J for resetting to zero the associated numeral wheel. This condition is 80 illustrated in Fig. 5, as also the accompanying disablement of backstop and restraining devices of which I shall next treat.

The before-mentioned ratchet element of each of the transmission gears E² takes the 90 form of a circular series of lugs or teeth 10 projecting from the right hand side. On the same frame cross rod 11 there is journalled a disc 12 carrying a driving pawl 13 of sufficient width to extend within the circle 95 of said ratchet lugs 10, as shown in Fig. 9. This pawl is pivoted to the disc intermediate its ends and a spring 14 throws its acting end outward into driving engagement with the ratchet lugs, as clearly shown in Fig. 1. 100 The disc is compounded with a driving gear 14 which is in mesh with a segment 15 that may be differentially oscillated by key depression in any suitable manner but preferably by connections of the character shown 105 in my aforesaid Patent No. 1,156,600.

The said ratchet lugs, besides serving as an element of the pawl and ratchet driving means, also serve for back-stopping purposes. There is a pawl 16 pivoted above 110 each gear wheel E², said pawl being preferably of yoke form as to its hub portion, as clearly seen in Fig. 2. The front end of this pawl is designed to engage between the ratchet lugs, as illustrated in Fig. 1, a spring 115 17 being applied to enforce this engagement which is effective to prevent rotation of the gear wheel E² in a clockwise direction and consequently prevent backward turning of the associated numeral wheel. The rear end 120 of said pawl is offset out of the plane of the ratchet lugs and extends into the plane of the right hand portion of the driving pawl 13 for the purpose of disabling that pawl when the numeral wheel is to be turned 125 backward to zero.

The arrangement for collectively disabling the pawls 16 and thereby the driving pawls 13 is the same as that shown in my said Patent No. 1,326,504. A rock shaft 18 is 130

cut out to form diametrical flat faces overlying the offset rear arms 16^a of the pawls 16, as shown in Fig. 1. The rocking of said shaft in a clockwise direction will depress 5 these arms of said pawls and not only disengage their forward ends from the ratchet lugs but also cause said offset arms 16^a to operate upon the driving pawls and disengage them from the ratchet lugs, as illustrated in Fig. 7. It will be noted that the zeroizing handle which appears in dotted lines in this figure of the drawings and is designated W is represented as having been drawn forward and it will be recalled that this has the 10 effect of rocking the shaft S in a counter-clockwise direction to bring various parts to zeroizing condition, as hereinbefore explained. This same rocking of the shaft S rocks the shaft 18. This is accomplished 15 through the medium of a crank arm S' on the left-hand end of said shaft S which crank arm carries a roller stud s operating in a cam slot of an arm 20, the latter having a bifurcated upper end which embraces a 20 stud upon a crank arm 18^a secured to the left-hand end of the rock shaft 18.

Now for the purposes of the individual zeroizing to which the present invention particularly pertains, I make provision for disabling a back-stop pawl 16 and companion driving pawl 13 by depression of the key lever which, as before described, serves to individually set parts for effecting backward turning of a single numeral wheel. The 30 units key lever 8^b and each of the other key levers 8^c carries a stud 8^e which occupies the cam slot 21^a of the upper branch of a bell crank lever 21. The rearwardly extending arm of this lever is pivoted to a plate 22 which is slotted to engage a guiding frame stud 23 and which has a forwardly and upwardly curved branch 22^a underlying a finger 16^b which projects forward from the yoke of the back-stop pawl 16. Depression 35 of the lever 8^c, as illustrated in Fig. 5, rocks the bell crank lever 21 and elevates the plate 22 with the effect of disengaging the said back-stop pawl and the driving pawl 13 from the ratchet lugs, and thereby releasing 40 the numeral wheel for backward rotation.

The plate 22 serves the further function of disabling certain devices which control the ratchet and pawl driving and driven elements to prevent the driven element from 45 running ahead of the driving element. These devices are disclosed in the aforesaid Gooch Patent No. 1,150,937, and comprise a notched disc 30 secured to the driving gear 14, and a mutilated pinion 31 coacting with 50 said notched disc and compounded with a pinion 32 which is in mesh with the transmission gear wheel E². This pinion structure is mounted slidably upon a shaft 34, which is itself slidable through its bearings 60 upon the frame of the machine. The pur-

pose of having the shaft slidable is the same as in the construction of my said Patent No. 1,326,504, to wit, that of providing for lateral displacement of all of the pinion structures by the act of pulling forward the zeroizing handle W. The particular purpose in the present instance of mounting the pinion structures to slide upon said shaft is to provide for any one of said structures being individually displaced laterally. It will 75 of course be understood that the mutilated pinion 31 must not remain in coacting relationship to the notched disc when the associated numeral wheel is to turn backward to zero, because if so the backward turning 80 of said numeral wheel would involve turning of the said notched disc and the driving wheel 14 and action of its key driven connections. The pinion 32 is made of such breadth as to maintain engagement with the 85 transmission gear wheel E² when the pinion structure has been slid a distance to the left sufficient to remove the mutilated pinion from the plane of the notched disc.

The arrangement for individually displacing a pinion structure is of the following description, reference being had especially to Fig. 4 and the description being confined to one set of the devices of which of course there is a set for each numerical 95 order in the machine. A laterally shiftable yoke 40 is supported upon a shaft 41 and has a fork 40^a which occupies an encircling groove of an extension 32^a of the pinion hub. A spring 42 coiled about the shaft 41 100 between a division plate of the machine frame and the left side of said yoke normally holds the latter over to the right with the mutilated pinion in coacting relationship to the notched disc. The aforesaid 105 plate 22, which is elevated by the special key lever, has an upwardly extending cam finger 22^b adapted to operate upon a horizontally extending finger 40^b of the yoke 40. Normally the cam portion of said finger 22^b is 110 below the yoke finger 40^b, as illustrated in Fig. 4, but when the plate 22 rises said cam portion drives the yoke to the left and effects the desired lateral displacement of the pinion structure. The yoke is prefer- 115 ably guided and steadied in its shifting movements and prevented from tilting so as to impose undue friction upon the pinion structure by forming it with a lug 40^c which occupies an opening in one of the division plates of the machine frame work, as clearly illustrated in Fig. 4.

It will now be clear that depression of one of the special key levers will remove all restraint to backward rotation of the associated numeral wheel and bring about such rotation by the spring J, supplemented if need be by the positive action of the stud 6^b upon the lower rear branch H³ of the carrying lever H in the manner already 130

pointed out. By way of instancing a simple example of the uses of the invention let it be supposed that 444 is registered upon the numeral wheels and that 4 is to be added in the units order but that the user inadvertently strikes the 5 key, raising the registration to 449 whereas it should be raised only to 448. Now under the old system either the entire registration would be canceled and the calculation done over again, or subtraction would be done by way of complemental adding, which would consist in depressing all of the 9 keys. The correction can be made by the use of the present invention in a much simpler way than either of those above mentioned. Thus the zeroizing key of the first order would be depressed, turning the units wheel back to zero and then the 8 key would be depressed in that order so that the correct registration would thereupon appear. To instance a more difficult situation wherein it may be assumed that a long series of calculations has been performed and then errors are made causing erroneous carries to have taken place; let us suppose that the machine has nine rows of keys and ten numeral wheels with the usual 9 key only in the tens order, and that after the series of calculations have been performed the wheels read 0,345,678,987 and to this it is desired to add 500,060 but that the operator inadvertently adds 600,040. This of course would cause several transfer or carrying operations to take place. To avoid having to cancel the entire calculation and begin all over again the correction could be made as follows: by first depressing the individual zeroizing keys in the second and sixth orders, thereby restoring the two wheels in those orders to zero; then depressing the 8 key in the second order and the 6 key in the sixth order, replacing the original registrations in those two orders; then depressing the 5 key in the sixth order and all the 9 keys to the left; and finally depressing the 6 key in the second order and all the 9 keys to the left; and the correct registration of 0,346,179,047 will result.

It remains to point out how the various yokes 40 are simultaneously shifted when all of the wheels are to be reset to zero. It will be recalled that in such a zeroizing operation the rock shaft 18 acts as illustrated in Fig. 7, motion being imparted to it through the medium of its crank arm 18^a. This same crank arm, and a similar one 18^c secured to the right hand end of said shaft (Fig. 4) control the sliding shafts 34 and 41. The latter is connected to the shaft 34 by an arm 34^c so as to move laterally in unison with said shaft 34. The arms 18^a and 18^c have rearwardly extending portions with cam formations 18^d and 18^e to operate upon the ends of the shaft 34. Normally the said arms are rearward and the shaft 34 is in its right hand position, as illustrated in Figs. 2 and 4, being so held by the offset portion of the arm 18^a. Upon the rocking of the shaft 18 the said arms swing forward and the cam portion 18^e of the arm 18^c operates upon the right-hand end of the shaft 34 as the offset portion of the arm 18^a swings past the left-hand end of said shaft. This results in shifting of the shaft 70 to its left-hand position and the other shaft 41 shifts with it. This other shaft carries collars 41^a (Fig. 2) which engage the several yokes 40 for shifting all of them to the left, and thereby laterally displacing all of the 80 pinion structures.

Passing now to the matter of splitting or subdividing the machine, the purpose here is to interrupt the carry-transmission at the point where it is desired to divorce one section of the accumulator from the other. It will be understood that carry-transmission involves the turning of a sun gear E in a counter-clockwise direction whereby the planet pinion D is rotated on its own axis 90 in a clockwise direction and correspondingly advances the numeral wheel A. This latter result is ensured by preventing backward turning of the gear wheel A' which carries said planet pinion. By freeing that gear 95 wheel for backward rotation it may be caused to take up the carry movement so that the latter will be diverted, and therefore dissipated so far as the numeral wheel is concerned. Therefore in order to interrupt the carry-transmission, and thereby split or subdivide the accumulator, I utilize the before described disablement of back-stop and driving pawls and overthrow-preventing devices (which disablement results 100 in freeing a planet carrying gear A' for reverse turning), and so accomplish the splitting or subdividing, in conjunction with the application of a stop or holding device to the numeral wheel. To this end the keys 110 8^a are pivotally mounted upon the forward ends of the levers 8^c so that in addition to depressing those levers for zeroizing purposes, as hereinbefore explained, any one of said keys may be further operated to 115 apply the stop or holding device to the associated numeral wheel. As there would never be occasion for so operating upon the units wheel, the key 8 for individually zeroizing this wheel is fixedly mounted upon the 120 front end of the lever 8^b.

The stop or holding device supplied for each of the other wheels is in the form of a lever 50 journaled upon the frame cross rod 3 and carrying upon its rear upturned end a friction pad 50^a to engage the periphery of the numeral wheel. The forward arm of this lever is turned up in the form of a hook 50^b which is adapted to be engaged by a downturned prong 8^d of the key 8^a. A 130

lower branch 8^e of said key carries a stud 8^f occupying a limiting slot 8^g in the lever 8^e. A spring 52 is fastened at one end to said stud and at the other to the frame of the machine and normally holds the key rocked forward on its pivot and the lever 8^e elevated, as illustrated in Fig. 1.

The angular relationship of the key 8^a and its supporting lever 8^e is such that direct downward pressure upon the key does not tend to rock it rearward upon its pivot but rather the contrary, so that the lever will be depressed just as though the key were an integral part of it. However, the key may be forced rearward at the will of the operator while the lever 8^e is being depressed or before, with the result of establishing the split. This rearward rocking and depression of the key causes its prong 8^h to lower the forward arm of the lever 50 and force the pad 50^a against the periphery of the numeral wheel, as illustrated in Fig. 6.

Preferably the key is rocked rearward before depressing its supporting lever so as to ensure the engagement of its prong with the brake lever, and so also to ensure that any registration which the associated wheel may happen to be showing will be preserved.

As it is desirable to provide for maintaining the split adjustment without necessitating continued holding down of the special key, I provide for latching it down. Thus it has a depending hooked finger 8^h which is adapted to engage in a notch 54 of the enclosing casing 55 of the machine.

The wheel-stopping lever 50 is preferably made of flat metal, as best shown in Fig. 4 and has sufficient resiliency to provide for maintaining pressure of the pad 50^a against the periphery of the wheel, the metal yielding somewhat to the force applied in the depression of the key when rocked rearward. This resiliency also permits the slight further rearward rocking of the key to engage its hook with the detaining notch. The stop lever is so proportioned as to release itself by gravity from contact with the wheel but in order to insure its release I form the lower branch 8^e of the key 8^a with a shoulder 8^f to act against the under side of the lever hook 50^b (see Fig. 1).

When a key 8^a is used for the purpose of effecting a split or subdivision of the accumulator it does not lower to the same extent as in the case of the use of the key for zeroizing purposes. This will be noted upon comparison of Figs. 5 and 6, the former representing the key as depressed for zeroizing and Fig. 6 illustrating it as depressed and rearwardly rocked for splitting or subdividing of the accumulator. From this it follows that the several disabling devices are not moved to the same extent. However

ablement. Thus the back-stop pawl 15 is rocked sufficiently to fully disengage it from the ratchet lug 10 and the driving pawl 13 is likewise disengaged from a lug of the gear wheel E². So also is the mutilated pinion 31 shifted sufficiently to disengage it from the toothed disc 30. In short the plate 22 is raised far enough to accomplish the necessary disablement of devices which normally would prevent reverse turning of the gear wheel E². The hooks 2^a and 4^a are not called upon to perform any functions in connection with this splitting or subdividing of the accumulator, so that the circumstance of their not being thrown to their operative positions when a key is used for splitting purposes, is of no consequence.

Reverting to the subject of backward turning of wheels to zero and utilization of carrying springs for such purpose and the means for positively performing the operation, these positively acting means are obviously capable of doing the work to the exclusion of any spring action, and, under such speed of manipulation as commonly attained and practiced by experienced and skillful users of these machines, the positive means in question will so act in their direct response to such manipulation. Thus the backward turning of wheels to zero will be effected by the driving of the studs 6^b down against the rearward branches H³ of the carrying levers without the springs J being actually called upon to do any of the work. On the other hand upon a slow pull on the zeroizing handle or slow depression of zeroizing keys, the springs will be in the ascendency and will have effected the backward turning of wheels to zero before the studs have made contact with the carrying levers.

I claim:

1. The combination of numeral wheels, reciprocating-key-driven actuators, one-way driving connections between the same and the respective wheels, carrying mechanism, and individual zeroizing means, a selected member of which disables the driving connections between an actuator and a wheel and resets such wheel to zero independently of other wheels by backward turning of the selected wheel.

2. The combination of numeral wheels, reciprocating key-driven actuators, one-way driving connections between the same and the respective wheels, carrying mechanism, including springs tensioned by the wheels, devices for holding the wheels against backward turning, and individual zeroizing means, a selected member of which disables one such device and the driving connections between the associated actuator and wheel to affect return to zero by backward turning of the selected wheel.

3. The combination of numeral wheels, reciprocating key-driven actuators, one-way

driving connections between the same and the respective wheels, carrying mechanism, and individual zeroizing means, a selected member of which disables the driving connections between an actuator and a wheel, and resets such wheel to zero independently of other wheels by backward turning of the selected wheel; together with means for simultaneously disabling all of the driving connections between the actuators and wheels for the simultaneous resetting of all of the wheels to zero.

4. The combination of numeral wheels, reciprocating key-driven actuators, one-way driving connections between the same and the respective wheels, carrying mechanism including springs tensioned by the wheels, devices for holding the wheels against backward turning, and individual zeroizing means, a selected member of which disables one such device and the driving connections between the associated actuator and wheel to effect return to zero by backward turning of the selected wheel; together with means for simultaneously disabling all the holding devices and all of the driving connections between actuators and wheels to effect simultaneous return to zero of all the wheels.

5. The combination of numeral wheels, reciprocating key-driven actuators, one-way driving connections between the same and the respective wheels, devices for preventing the wheels from running ahead of the actuators, carrying mechanism, and means for individually disabling the driving connections and the said preventing device between an actuator and wheel and resetting such wheel to zero independently of other wheels by backward turning of the selected wheel.

6. The combination of numeral wheels, reciprocating key-driven actuators, one-way driving connections between the same and the respective wheels, devices for preventing the wheels from running ahead of the actuators, carrying mechanism, and means for individually disabling the driving connections and the said preventing device between an actuator and wheel and resetting such wheel to zero independently of other wheels by backward turning of the selected wheel, together with means for simultaneously disabling all of the driving connections and preventing devices between the actuators and wheels and resetting all of the wheels to zero.

7. The combination of numeral wheels, key-driven reciprocating actuators, pawl and ratchet driving connections between the same and the respective wheels, springs tensioned by the wheels, back-stop pawls, and means for individually disabling a back-stop pawl and a pawl and ratchet driving connection to effect return to zero of a wheel by its spring independently of other wheels.

8. The combination of numeral wheels, key-driven reciprocating actuators, pawl and

ratchet driving connections between the same and the respective wheels, springs tensioned by the wheels, back-stop pawls, and means for individually disabling a back-stop pawl and a pawl and ratchet driving connection to effect return to zero of a wheel by its spring independently of other wheels, together with means for simultaneously disabling all the back-stop pawls and all the pawl and ratchet driving connections to effect return of all the wheels to zero by their springs.

9. The combination of numeral wheels, reciprocating key-driven actuators, one-way driving connections between the same and the respective wheels including transmitting gear wheels, pinions in mesh with said wheels, mutilated gear pinions compounded with said pinions respectively, notched discs reciprocated by the actuators and cooperating with said mutilated pinions respectively, and means for individually displacing a pinion and mutilated pinion.

10. The combination of numeral wheels, reciprocating key-driven actuators, one-way driving connections between the same and the respective wheels including transmitting gear wheels, pinions in mesh with said wheels, mutilated gear pinions compounded with said pinions respectively, notched discs reciprocated by the actuators and cooperating with said mutilated pinions respectively, and means for individually displacing a pinion and mutilated pinion, together with means for simultaneously displacing all of said pinions.

11. The combination of numeral wheels, reciprocating key-driven actuators, one-way driving connections between the same and the respective wheels including transmitting gear wheels, pinions in mesh with said wheels, mutilated gear pinions compounded with said pinions respectively and laterally shiftable with them, notched discs reciprocated by the actuators and cooperating with said mutilated pinions respectively, and means for individually shifting a pinion and mutilated pinion laterally to disengage the latter from the associated notched disc.

12. The combination of numeral wheels, reciprocating key-driven actuators, one-way driving connections between the same and the respective wheels including transmitting gear wheels, pinions in mesh with said wheels, mutilated gear pinions compounded with said pinions respectively and laterally shiftable with them, notched discs reciprocated by the actuators and cooperating with said mutilated pinions respectively, and means for individually shifting a pinion and mutilated pinion laterally to disengage the latter from the associated notched disc, together with means for simultaneously shifting laterally all the pinions.

13. The combination of numeral wheels,

- reciprocating key-driven actuators, one-way driving connections between the same and the respective wheels including transmitting gear wheels, pinions in mesh with said 5 wheels, mutilated gear pinions compounded with said pinions respectively, a supporting shaft for said pinions on which they are slideable, notched discs reciprocated by the actuators and cooperating with said pinions respectively, means for sliding the pinions on the shaft, and means for shifting the shaft itself.
14. The combination of numeral wheels, reciprocating key-driven actuators, one-way 15 driving connections between the same and the respective wheels including transmitting gear wheels, pinions in mesh with said wheels, mutilated gear pinions compounded with said pinions respectively, a supporting shaft 20 for said pinions on which they are slideable, notched discs reciprocated by the actuators and cooperating with said pinions respectively, and key levers and cams for sliding the pinions on the shaft.
15. The combination of numeral wheels, reciprocating key-driven actuators, one-way driving connections between the same and the respective wheels including transmitting gear wheels, pinions in mesh with said 25 wheels, mutilated gear pinions compounded with said pinions respectively, a supporting shaft for said pinions on which they are slideable, notched discs reciprocated by the actuators and cooperating with said pinions 30 respectively, yokes for shifting the pinions, springs applied to the yokes, and key-levers and cams for operating the yokes in opposition to their springs.
16. The combination of numeral wheels, reciprocating key-driven actuators, one-way 40 driving connections between the same and the respective wheels including transmitting gear wheels, pinions in mesh with said wheels, mutilated gear pinions compounded 45 with said pinions respectively, a supporting shaft for said pinions on which they are slideable, notched discs reciprocated by the actuators and cooperating with said pinions respectively, yokes for shifting the pinions, 50 springs applied to the yokes, a shaft slideably supporting the yokes, means for individually shifting the yokes, and means for collectively shifting them.
17. The combination of numeral wheels, reciprocating key-driven actuators, one-way 55 driving connections between the same and the respective wheels including transmitting gear wheels, pinions in mesh with said wheels, mutilated gear pinions compounded 60 with said pinions respectively, a supporting shaft for said pinions on which they are slideable, notched discs reciprocated by the actuators and cooperating with said pinions respectively, yokes for shifting the pinions, 65 springs applied to the yokes, a shaft

slidably supporting the yokes, key-levers and cams for individually shifting the yokes, and a handle and connections for shifting the yoke-supporting shaft.

18. The combination of register wheels 70 having cams and sun gears, intermediate gears geared to higher order wheels, gear carriers whose gears mesh with said sun gears and said intermediate gears, gear-carrier oscillating members controlled by the 75 cams, springs applied to said members, devices for holding the wheels from backward turning, normally inactive devices for locking the intermediate gears, and means for individually disabling a holding device and 80 enabling a locking device for effecting return to zero of a wheel by its spring independent of other wheels.

19. The combination of register wheels having cams and sun gears, intermediate 85 gears geared to higher order wheels, gear carriers whose gears mesh with said sun gears and said intermediate gears, gear-carrier oscillating members controlled by the cams, springs applied to said members, devices for holding the wheels from backward turning, normally inactive devices for locking the intermediate gears, and means for individually disabling a holding device and 90 enabling a locking device for effecting return to zero of a wheel by its spring independent of other wheels, together with means for simultaneously disabling all the holding devices and enabling all the locking devices, for effecting return to zero of all 95 the wheels by their springs.

20. The combination of register wheels having cams and sun gears, intermediate gears geared to higher order wheels, gear carriers whose gears mesh with said sun 105 gears and said intermediate gears, gear-carrier oscillating members controlled by the cams, springs applied to said members, normally retracted locking levers for locking the intermediate gears, independently operable rock-arms for setting said locking levers, and keys and connections for operating 110 the rock arms.

21. The combination of register wheels having cams and sun gears, intermediate 115 gears geared to higher order wheels, gear carriers whose gears mesh with said sun gears and said intermediate gears, gear-carrier oscillating members controlled by the cams, springs applied to said members, normally retracted locking levers for locking the intermediate gears, independently operable rock-arms for setting said locking levers, keys and connections for operating 120 the rock arms, and a rocking structure common to said arms for collectively operating 125 them.

22. The combination of register wheels having cams and sun gears, intermediate gears geared to higher order wheels, gear 130

carriers whose gears mesh with said sun gears and said intermediate gears, gear-carrier oscillating members controlled by the cams, springs applied to said members, re-

means for changing control of said gearing to effect backward turning of wheels to zero, and for positively actuating the gearing to so turn the wheels.

5 ciprocating actuators, transmission gears for the respective wheels, pawl and ratchet driving connections between said actuators and said trassmission gears, back-stop pawls engaging the latter, pinions in mesh with the 10 transmission gears, mutilated pinions compounded with said pinions, notched discs reciprocated by the actuators and coacting with said mutilated pinions, normally retracted locking levers for locking the aforementioned intermediate gears, independently operable rock arms for setting said locking levers, key-levers operating upon said rock-arms respectively, and members connected to said key-levers and operating to disable 15 the back-stop pawls and the pawls of the driving connections and also the mutilated pinions.

23. The combination of numeral wheels, planetary gearing, connections for carrying transmission through the planetary gearing, and means for varying control of the latter whereby to dissipate the carry-transmission at will.

24. The combination of numeral wheels, 30 key-driven actuators, planetary gearing, back-stop means applied to elements thereof advanced by the actuators, connections for carry-transmission through the planetary gearing, and means for holding a higher 35 order wheel and disabling associated back-stop means.

25. The combination of numeral wheels, planetary gearing applied thereto, actuators geared to the planet-gear carriers, back-stops 40 for the latter, connections for carry-transmission from wheel to wheel through the planetary gearing, a stop for the higher order wheel, and a key for applying said stop and simultaneously disabling the back-stop for 45 the planet-gear carrier associated with said wheel.

26. The combination with key-driven actuators, numeral wheels, and carrying mechanism; of means for utilizing the latter mechanism to turn the wheels backward to zero 50 under positive actuation.

27. The combination with key-driven actuators, numeral wheels, and carrying mechanism; of means for utilizing the latter mechanism to turn the wheels backward to zero 55 individually under positive actuation.

28. The combination with key-driven actuators, numeral wheels, and carrying mechanism; of means for utilizing the latter mechanism to turn the wheels backward to zero 60 individually or collectively under positive actuation.

29. The combination with key-driven actuators, numeral wheels, and carrying mechanism, comprising differential gearing; of 65

70 means for changing control of register wheels having cams and sun gears, intermediate gears geared to higher order wheels, gear carriers whose gears mesh with said sun gears and said intermediate gears, gear-carrier oscillating members controlled by the cams, 75 springs applied to said members, devices for holding the wheels from backward turning, normally inactive devices for locking the intermediate gears, and means for disabling the devices which hold the wheels against backward 80 turning and bringing into action the said locking devices, and positively operating the gear-carrier oscillating members to backwardly turn the numeral wheels to zero.

31. The combination of register wheels 85 having cams and sun gears, intermediate gears geared to higher order wheels, gear carriers whose gears mesh with said sun gears and said intermediate gears, said carriers having gear segments, levers engaged with 90 the cams and segments in mesh with those of the gear carriers, springs applied to said levers, devices for holding the wheels against backward turning, normally inactive devices for locking the intermediate gears, and means 95 for disabling the devices which hold the wheels against backward turning and bringing into action the said locking devices, and for positively operating upon the said levers to swing the gear carriers and backwardly 100 turn numeral wheels to zero.

32. The combination of register wheels having cams and sun gears, intermediate gears geared to higher order wheels, gear carriers whose gears mesh with said sun gears 105 and said intermediate gears, gear-carrier oscillating members controlled by the cams, springs applied to said members, normally retracted locking levers for locking the intermediate gears, independently operable rock-arms for setting said locking levers, and for 110 positively operating upon the gear-carrier oscillating members, and keys and connections for operating the rock-arms.

33. The combination of register wheels 115 having cams and sun gears, intermediate gears geared to higher order wheels, gear carriers whose gears mesh with said sun gears and said intermediate gears, gear-carrier oscillating levers controlled by the cams, 120 springs applied to said levers, a zeroizing rocking structure adapted to positively operate upon the said levers, and means also operated by said structure for locking the intermediate gears.

34. The combination of register wheels having cams and sun gears, intermediate gears geared to higher order wheels, gear carriers whose gears mesh with said sun gears and said intermediate gears, gear-carrier os- 130

cillating levers controlled by the cams, springs applied to said levers, normally re-tracted locking levers for locking the intermediate gears, independently operable rock-
5 arms for setting said locking levers, and for positively operating upon said gear-carrier oscillating levers, keys and connections for

operating the rock-arms, and a rocking structure common to said arms for collectively operating them.
